UNITED STATES PATENT OFFICE.

JACOB DAVID, OF BROOKLYN, NEW YORK.

IMPROVEMENT IN MECHANICAL MOVEMENTS.

Specification forming part of Letters Patent No. **222,872**, dated December 23, 1879; application filed November 7, 1879.

To all whom it may concern:

Be it known that I, JACOB DAVID, of Brooklyn, in the county of Kings and State of New York, have invented a new and useful Improvement in Mechanical Movements, which improvement is fully set forth in the following specification, reference being had to the accompanying drawings, in which—

Figure 1 shows my movement in side view. Fig. 2 is a plan or top view of the same.

Similar letters indicate corresponding parts.

My invention relates to mechanism for converting a rotary motion into a reciprocating motion; and it consists in the combination of toggle-levers pivoted together—one pivoted to a fixed support, and the other pivoted to a movable object—with a crank mounted on a revolving shaft, and a connecting-rod between the crank and the toggle-levers engaging the crank-pin and the pivot at the junction of the levers, so that while a reciprocating motion may be given to the movable object by a revolution of the shaft, the union and efficiency of the parts is preserved in any position of the toggle-levers, as hereinafter more fully set forth.

In the drawings, the letter A designates the toggle-levers; B, the crank, and C the driving-shaft. The toggle-levers A are connected together at one end by a pivot, d, and one is connected to a fixed support, E, by a pivot, f, while the other is connected to a movable object, G, by a pivot, h. The movable object G consists, in this example, of a jaw in an ore-crusher, of which the fixed support E is a portion of the frame. The crank B is fixed on the shaft C, and a rod, I, engaging the crank-pin and the pivot d at the junction of the toggle-levers, serves to connect the crank with the levers.

When a revolving motion is imparted to the

shaft C the toggle-levers A are alternately bent and straightened, thereby giving a reciprocating motion to the jaw G, and the arrangement of the parts is such that the jaw receives two distinct motions to each revolution of the shaft. By the pivots d f h the parts are kept united in any position of the toggle-levers, and their efficiency or utility is preserved.

When the toggle-levers are allowed to rest in notches at the points d f h, as in the ore-crushers now generally used, they are capable of but a very small motion, inasmuch as they are liable to become disunited at those points if moved to any great extent above and below the center-line.

What I claim as new, and desire to secure by Letters Patent, is—

A mechanical movement for converting a rotary motion into a reciprocating motion, embodying the combination of toggle-levers pivoted together at one end, and at their opposite ends pivoted, respectively, to a fixed support and a movable object, a revolving shaft provided with a crank, and a rod pivoted to the cranks and to the toggle-levers at their pivotal junction, forming a connection between the crank on the revolving shaft and the toggle-levers, whereby the revolving motion of the shaft transmits a continuous reciprocating motion to the movable object connected with the toggle-lever, substantially as described.

In testimony that I claim the foregoing I have hereunto set my hand and seal this 4th day of November, 1879.

JACOB DAVID. [L. S.]
